Primary Examiner — Vy N Koenig*(74) Attorney, Agent, or Firm* — Myers Wolin, LLC(57) **CLAIM**

The ornamental design for a combined bench and table assembly, as shown and described.

DESCRIPTION

FIG. 1 is a perspective view of a combined bench and table assembly showing our new design;
 FIG. 2 is a front elevation view thereof;
 FIG. 3 is a back elevation view thereof;
 FIG. 4 is a left side elevation view thereof;
 FIG. 5 is a right side elevation view thereof;
 FIG. 6 is a top plan view thereof; and,
 FIG. 7 is a perspective view showing the design in a different context.

The broken lines are for showing environment or for showing unclaimed elements only and form no part of the claimed design.
